Primary Examiner — John A Voytek

(57) **CLAIM**

The ornamental design for a pneumatic tyre for vehicle wheels, as shown and described.

DESCRIPTION

1. Pneumatic tyre for vehicle wheels
2. Pneumatic tyre for vehicle wheels

1.1 : Front

1.2 : Left

1.3 : Right

1.4 : Perspective

1.5 : Perspective

1.6 : Enlarged

2.1 : Front

2.2 : Left

2.3 : Right

2.4 : Perspective

2.5 : Perspective

2.6 : Enlarged

Broken lines in the drawings Figs. **1.1** and **2.1** are used for demarcation of the enlarged portions shown in Figs. **1.6** and **2.6**, respectively, and are not part of the claim.
